CRATE

William W. Birnstock, York, Pa.

Application March 19, 1930, Serial No. 437,121

17 Claims. (Cl. 217—20)

This invention relates to crates and has for its principal object the provision of means for materially strengthening the crate generally and also in the providing of vertical brackets associated with non-flat spacing strips at the bottom of the crate making the so-called grid work much more sturdy than the grid work in previous structures of this kind.

In the drawings:

Figure 1 is a vertical section thru a crate embodying my invention.

Figure 2 is a transverse vertical section.

Figure 3 is an enlarged view of one of the standards.

Figure 4 is a side elevation of Figure 3.

Figure 5 is a view of an end slat.

Figure 6 is a perspective of the standard in place.

My invention in its preferred form relates to milk bottle crates but it is obvious that features of the invention have utility in other fields. In the drawings the crate is formed of replaceable slats and the metal pieces are also replaceable altho the crate is in no sense whatsoever a knock-down crate, the idea of replacement being solely to be able to remove a part that has been damaged in handling, it being well known that milk crates to stand the treatment they are subjected to, must necessarily be of very sturdy materials.

At each of the four corners of the crate there is a vertical angle piece 10 having integral right-angled horizontal flanges 11 at top and bottom and also having integral lugs 12 with rounded inturned flanges 13 which receive and hold the inner angle-iron piece 14 which is driven vertically downward from the top, binding in place the five end strips and the five side strips which meet at that corner. The features so far described are not claimed in the present application and are described to clarify the description of other parts.

Each bottom end slat 15 and each bottom side slat 16 has on its lower surface a metal runner 17 which is secured to the bottom slat by means of fastening 18 which may be either screws or nails and which are preferably, tho not necessarily, countersunk. In ordinary custom the ends of these runners, which are ordinarily straps or bands, are bent sharply upwardly at right angles and rest against the transverse cleats or they are offset and extend above and rest on the angle pieces. In the first scheme the objection is that the ends of the bands tend to come out and catch on parts of the carrier mechanism, often resulting in the tearing off of this bottom reenforcing

I find I can secure a more satisfactory runner by cutting a short kerf 20, at or near the junction of the runner and the flange 11, extending upwardly into the slat at an angle of about 60° and by bending each end of the strap or band 17 to the same angle as at 19 and then applying the runner or band to the slat laterally, driving the band in with a firm fit and finally applying the fastenings 18. In this way there is no tendency for the band to gap and since I ordinarily apply one of the fastenings 18 very close to the upturned end 19 of the band there is no tendency of the end of the band or runner to be deflected downward into position where it could cause damage.

Inasmuch as a runner 17 is applied to each one of the four bottom slats prior to assembly, the presence or absence of the runner makes no difference in the method of assembly but it will be noted that each upturned end 19 is protected in part by the end of the angle piece 14 which normally has at each edge a slight flange which is engaged by the lip 13. The bottom slat, as best seen in Figure 5 is slightly grooved at each end 20 as at 21 to receive the outer angle 10 and the kerf 22 to receive the plug 12 is at the shoulder made by the shallow recess 27. I insure against a splitting from the end of the slat to the kerf by the screw or nail 29, the head of which need not be recessed as it lies in the horizontal crack between the bottom slat and the slat just above.

Near the bottom of the crate and extending from one end slat 15 to the other is a series of supporting rods 21 arranged in pairs to form a bottom rest for the bottles which the crate carries. The usual compartments are formed by the longitudinal rods 23 and by the transverse partition rods 24 which preferably lie just above the approximate longitudinal rods. The rods illustrated differ from the usual lacing strips only in being somewhat more sturdy and in the fact that each rod 21, 23 and 24 is independently removable from the crate by means illustrated and claimed in an application which I have previously filed. A plurality of parallel spacer strips 25 extend from side to side of the crate and each is perforated to receive all of the supporting rods 21. Each spacer strip is J-shaped in cross section with the rounded portion up, i.e., the portion 26

which surrounds the proximate transverse rods 24. I prefer that the holes to receive the supporting rods be positioned so that these bottom supporting rods shall easily clear the edge of the rounded portion 26 of the spacer strips, this for convenience in replacement of a rod, but if desired the edge of this rounded portion of the spacer strip may engage the supporting rod to make a slightly more firm connection.

10 Referring now particularly to Figures 3 and 4, I join the various rods of my grid by brackets 30 each consisting of a single stamping, the principal portions of which are a standard 31 and a base 32. Centrally the standard is perforated as 15 at 33 to receive the middle longitudinal rod 23 and at each side of the opening the standard is indented as at 33 and 34 to receive the middle transverse rod 24. It will be noted that the portions 33 and 34 are indented in opposite directions and that all of the brackets are alike, there being no sufficient advantage in making them rights and lefts to overcome the necessity for the additional trouble in assembly.

Near the top the standard is bent as at 35 and 25 is bent to U-shape at the top as at 36 ending in a downturned lip 37 between which and the offset back portion 38 is received the upper transverse rod 24, the lip and back having alined openings 39 to receive the upper longitudinal rod 23 which it will be noted locks the upper transverse 30 rod in place in the opening between the back 38 and the lip 37.

The base 32 is of sufficient transverse length to grip one bottom rod 21 of each of two proximate pairs and for this purpose is provided with the openings 40 which aline with openings in the spacer strip 25 which latter is gripped at its bottom by each of two reversely bent flanges or lips 41, the metal of the base preferably being recessed as at 42 between these portions. I prefer that the major portion of the bracket 30 shall be in the plane of the axes of the transverse rods and I also prefer that the major portion of the spacer strip 25 shall be vertical and therefore I 45 form an offset 44 in the base of the bracket to receive the rounded top portion 26 of the spacer strip.

By the provision of the spacer strip and the 50 associated standards I have formed a crate which is remarkably sturdy since the spacer strips by their locking engagement with the base of the bracket prevents absolutely any side to side movement of the upper longitudinal rods 23 and the 55 tying in of the middle transverse rods limits sharply the possibility of end to end movement, of the middle of the spacer strips 25. Side to side movement of the bottom supporting rods 21 is absolutely limited by the spacer strips and also by 60 the interlocking relation of the brackets thru their openings 40 which receive these rods.

What I claim is:

1. In a crate having sides, ends, partition rods at different levels joining opposite walls to form 65 bottle receiving compartments, and supporting rods joining opposite walls to form a bottom rest for the bottles; a spacer engaging one side of one lower partition rod throughout its exposed length and having openings to receive the adjacent supporting rods so as to lock the said one lower partition rod to said spacer, and a bracket engaging 70 said spacer, a plurality of supporting rods and one of the upper partition rods and having openings therethru to receive a plurality of partition rods located between the upper partition rod engaged

by the bracket and the lower partition rod engaged by the spacer.

2. The device of claim 1 in which the bracket is provided with means to prevent lateral movement of the bracket with respect to the spacer. 5

3. In a crate, a plurality of bottle supporting rods, a plurality of transverse spacers having openings therethru to engage snugly each of said bottle supporting rods, a bracket having a base resting upon the upper side of a spacer and having gripping relations with the spacer on the opposite side, said bracket having an extension provided with recesses and openings for interlocking partition wires above the spacer. 10

4. In a crate having a plurality of partition rods, a member receiving therethru a plurality of vertically alined rods and also receiving in interlocking engagement with said rods a plurality of vertically alined rods extending at right angles to the first mentioned rods, and spaced means for 20 anchoring said member to prevent lateral movement of certain of said rods, said rods mutually cooperating thru said interlocking engagement to produce a snug fit in said member. 15

5. A grid for a crate consisting of a plurality of intersecting partition rods forming bottle compartments, a plurality of bottom supporting rods, a plurality of bottom transverse rods each crossing all of the bottom supporting rods, a plurality of spacing members each adapted to receive a 25 transverse bottom rod and having openings therethru to receive the bottom supporting rods to lock the transverse bottom rod to the spacing member, and a plurality of brackets each engaging a spacing member on two sides receiving 30 thru openings therein two proximate bottom supporting rods each bracket having an extension receiving and locking other pairs of intersecting rods. 35

6. A spacing strip for a crate, comprising a 40 member J-shaped in cross section, the rounded portion receiving snugly a partition rod, said member having in its flat portion a plurality of openings to receive snugly transverse positioning rods, said openings being adjacent the rounded portion so that the rods passing therethru engage the partition rod whereby to lock the said partition rod within said rounded portion. 45

7. A member for making rigid a plurality of rods crossing each other to form partitions, consisting of a base having a recess to receive a rod and having an opening to receive a rod at right angles to said rod to lock said rod in the recess; a standard having a recess to receive a rod parallel to the first rod and having a hole therethru to receive a further rod to lock such adjacent rod in the standard recess; and means integral with the member for locking together two rods crossing each other at right angles between the first rod and the parallel rod. 55

8. In a crate having replaceable slats forming panels, replaceable bottle supporting rods near the bottom of the crate, a plurality of replaceable transverse rods just above the bottle supporting rods, spacing elements having openings there- 65 thru to receive the bottle supporting rods, a plurality of brackets, each bracket having an offset portion to receive a bottom transverse rod, a plurality of partition rods in vertical alinement with said transverse rod, said brackets each having 70 holes therethru to receive a plurality of longitudinal partition rods and having spaced openings therein to receive two laterally spaced bottle supporting rods neither of which is in vertical alinement with the partition rods, and means for se- 75

curing the brackets to the bottom of the respective spacing elements whereby all longitudinal rods are positively locked against side to side movement.

5 9. In a crate having end and side slats, means at each corner for locking the slats in place, rods extending from side to side and from end to end of the crate arranged in different horizontal planes to form bottle compartments, a plurality 10
10 of bottle supporting rods extending from end to end of the crate and below the previously mentioned rods, a plurality of transverse rods extending from side to side of the crate just above the bottle supporting rods, a plurality of spacing 15
15 strips each snugly engaging one of said last mentioned side to side rods and having openings therethru to receive the bottle supporting rods, and means engaging the spacing members to lock the rods above the bottle supporting rods to the spacing member, said means having integral extensions receiving and locking the partition rods located above the rod which is locked to the spacing member.

10. A bracket for a milk crate with crossed partition rods, a plurality of bottle supporting rods arranged in pairs beneath the partition rods and having spacing members associated with some of the rods, said bracket consisting of a single stamping having an extended base recessed 25
30 to receive a partition rod and provided with spaced lugs to grip a spacing member, a standard rising from said base and ending with a downturned lip to receive a rod parallel to the base and having alined openings in the standard, one 35
35 of said openings located to receive a crossing rod to lock the just-mentioned rod in the recess formed by the lip, said standard having between the lip and base a vertically elongated slot and laterally of such recess a pair of oppositely directed indentations, alined openings in said base 40
40 for receiving said supporting rods.

11. A bracket for interlocking four rods in vertically alined pairs crossing at right angles,

consisting of a member having a central elongated slot to receive one rod and transversely thereof two complementary, oppositely directed indentations to receive the proximate rod which will lock the first rod in one end of the slot, said member being offset to form a back parallel to the body of the member, said back having a downturned lip parallel with the back and body to form a recess for receiving a rod parallel to the second mentioned rod, said back and lip having alined openings therethru for receiving the fourth rod which will lock the third rod in said recess, and means for anchoring the member to prevent lateral movement of the fourth rod.

12. The device of claim 11 in which the anchoring means is an integral base of the bracket having interlocking connection with a plurality of other intersecting rods.

13. The device of claim 11 in which the anchoring means is a base having spaced holes to receive snugly further rods parallel to the third rod.

14. The device of claim 11 in which the anchoring means is a base having inturned flanges and in proximity therewith an elongated recess 25
25 to receive the member which is engaged by the flanges.

15. A T-shaped bracket for positioning the rods of a milk crate having two spaced holes in its standard to receive two parallel rods and 30
30 having near the end of each arm a hole to receive a rod not in alinement with the two parallel rods.

16. The device of claim 15 in which the bracket is recessed for reception of three parallel rods each passing closely one of the said spaced holes. 35

17. The device of claim 15 in which the bracket is recessed for reception of three parallel rods each passing closely one of the said spaced holes and is provided with gripping means to engage a member having locking engagement with the 40
40 rods which pass thru the holes in the two arms of the T-bracket.

WILLIAM W. BIRNSTOCK.
